CONVERTIBLE DINING AND GAME TABLE

Marvin O. Wilbourn, 2725 Meadowbrook Drive,
Boise, Idaho 83705

Filed July 20, 1972, Ser. No. 273,568

Term of patent 14 years

Int. Cl. D6—03

U.S. Cl. D6—27

FIG. 2

FIG. 1 is a front top perspective view of the convertible dining and game table of the present invention showing to advantage the overall ornamental design of the top and pedestal of my new design.

FIG. 2 is a front perspective view of the convertible dining and game table of the invention with the top removed to show the several game portions of the table and an intermediate insert of my new design exploded away for illustrative purposes.

FIG. 3 is a bottom perspective view of the table with the removable top exploded away.

I claim:

The ornamental design for a convertible dining and game table, substantially as shown and described.
